UNITED STATES PATENT OFFICE

DANIEL APPEL, OF CLEVELAND, OHIO, ASSIGNOR TO THE UNION PAPER BAG MACHINE COMPANY, OF PHILADELPHIA, PENNSYLVANIA.

PAPER BAG.

SPECIFICATION forming part of Letters Patent No. 340,078, dated April 20, 1886.

Application filed October 19, 1885. Serial No. 180,265. (Model.)

To all whom it may concern:

Be it known that I, DANIEL APPEL, a citizen of the United States, residing at Cleveland, county of Cuyahoga, and State of Ohio, have invented certain new and useful Improvements in Paper Bags, fully described and represented in the following specification and the accompanying drawings, forming a part of the same.

10 This invention relates, generally, to that class of paper bags which are made from a single piece of paper which is folded transversely upon itself and united at its edges, so as to form a bag having two side seams and a seam-15 less bottom.

15 The invention relates particularly, however, to a bag of this class which is provided with what is known as a "satchel-bottom."

20 The bags constructed according to the present invention may be made from a continuous web or from detached sheets or blanks, the same as is the case with most of the ordinary forms of paper bags. In carrying the invention into practical operation it will usually, 25 however, be found most desirable to employ detached blanks previously cut to the proper form. The operation of making a bag from such a blank is therefore illustrated in the present case.

30 As the construction of the bag can be best understood from a detailed description of the manner in which the blank is treated in forming it, such description will now be given, reference being had to the accompanying drawings, in which—

35 Figure 1 is a view of a portion of a blank of suitable form for making the bag, the dotted lines indicating the lines upon which the blank is folded in the formation of the bag. Figs. 40 2 to 6, inclusive, illustrate the various steps in the formation of the bag. Figs. 7 and 8 are views of the opposite sides of the completed bag. Fig. 9 is a perspective view of the bottom of the bag when distended, and Fig. 10 is an inside view of the same.

45 Referring to said figures, it is to be understood that the sheet or blank, a part of which is shown in Fig. 1, is of rectangular form and of the proper length and width to make the 50 bag of the desired proportions. This blank

may, and preferably will, be first creased on some or all of the dotted lines indicated to aid in making the several folds necessary in the formation of the bag.

The blank, either with or without the creasing, is first folded transversely on the line 10 10, so as to bring the portion B, which forms one side of the bag, over onto the portion C, which forms the bottom of the bag, and the portion A, which forms the other side of the bag, as shown in Fig. 2. This being done, the narrow portion d, at one side of the portion B, is folded inward on the line 12 12, thus at the same time forming diagonal folds on the lines 9 12 at that side of the blank, and bringing the 55 triangular portion b at that side of the blank into the position shown in Fig. 2, so that the line 10 12 will coincide with the line 8 12. The portion d is then folded back to its original position, thus folding the portion b upon the line 10 12 and bringing it beneath the side portion, B, as shown in Fig. 3. The portions d and b at the other side of the blank are then treated in like manner. The portion d is folded inward on the line 12 12, thus making diagonal folds on the lines 9 12 at the other side of the blank, and bringing the portion b at that side of the blank to the position shown in 60 Fig. 3. The portion d is then folded back to its original position, thus folding the portion b upon the line 10 12 and bringing it beneath the side portion, B, as shown in Fig. 4. The portions d and b are then folded back to their original positions, thus folding the portion b upon the line 10 12 and bringing it beneath the side portion, B. It will of course be understood that both of the portions d may be folded inward and then outward simultaneously, or that the second of the portions may be folded 65 inward before the first is folded back to its original position. After the portions b at both sides of the blank have been folded inward beneath the portion B, as just described, the portion B is turned upward away from the portion A and is folded outward on the line 13 13, and at the same time diagonal folds are made upon the lines 7 13, which cause the narrow marginal portions e at the edges of the portion B to be folded inward on the lines 75 13 15, as shown in Fig. 4. After this is done the side portion, B, and the bottom-forming portion C are folded over on the line 11 11, as shown in Fig. 5, thus causing the lines 13 13 and 14 14 to coincide, and at the same time 70 75 80 85 90 95 100

folding the triangular portions *a* at each side of the blank centrally upon the lines 8 11 and bringing the bottom-forming portion *C* to the top, where it projects for one-half of its width over the side portion, *B*, as shown in Fig. 5. After this is done the triangular portions *c* at the sides of the bottom portion, *C*, are folded inward on the lines 8 12 and laid down onto the bottom portion, *C*, thereby unfolding the 10 folds made on the lines 8 11 and 10 12 and forming diagonal folds on the lines 6 8, and causing the triangular portions *a* to overlie the triangular portions *b*, and the lines 8 12, 15 8 11, and 10 12 to coincide at each side of the blank, as shown in Fig. 6. After this has been done the side portions, *A* *B*, are folded over together on the coinciding lines 13 13 and 14 14, thereby carrying the bottom portion, *C*, over so that it overlaps the side portion, 20 *A*, as shown in Fig. 8, and at the same time unfolding the folds on the lines 6 14 and forming the diagonal folds on the lines 5 14, and causing the narrow marginal portions *f* of the side portion, *A*, to be folded over on the lines 25 14 16 onto the opposite side portion, *B*, as shown in Fig. 7, thus completing the formation of the bag.

It will be observed that by this manipulation of the blank a bag is formed which has a seam-less satchel-bottom. The triangular points formed by the triangular portions *c* and one-half of each of the triangular portions *a* and *b*, which correspond to the points of the diamond in an ordinary satchel-bottom bag which is 30 made from a tubular blank, may be pasted down to the bottom portion, *C*, or they may be turned outward and secured in that position so as to be upon the sides of the bag when 35

the latter is distended, as indicated by dotted lines in Fig. 9, or they may be allowed to remain loose. It is preferable, however, that they should be secured to the bottom portion, *C*, as shown.

It is of course to be understood that the portions *f*, or both the portions *f* and *e* and 45 also the outer edges of the triangular portions *a*, will be provided with suitable lines of paste to properly unite the plies of the paper to form the seams of the bag.

In conclusion, it is to be remarked that the 50 folding described may be varied considerably without departing from the essential features of the invention, and also that the form of the blank may be varied from that shown. The narrow marginal portions *e* may, if preferred, 55 be removed from the blank, and this will somewhat simplify the folding.

What I claim is—

1. A bag having two side seams and a seam-less bottom, and having the triangular points 60 formed at opposite sides of the bottom by bringing together the triangular portions *c* and the portions *a* *b*, substantially as described.

2. A bag having two side seams and a seam-less bottom, and having the triangular points 65 formed of the portions *a* *b* *c*, folded inward and secured to the bottom, substantially as described.

In testimony whereof I have hereunto set my hand in the presence of two subscribing 70 witnesses.

DANIEL APPEL.
